UNITED STATES PATENT OFFICE.

HERBERT E. COOLEY, OF WEST BEND, WISCONSIN.

NAIL-FEEDING MECHANISM FOR BARREL-NAILING MACHINES.

Application filed February 16, 1920. Serial No. 359,027.

To all whom it may concern:

Be it known that I, HERBERT E. COOLEY, a citizen of the United States, and a resident of the city of West Bend, county of Washington, and State of Wisconsin, have invented a new and useful Improvement in Nail-Feeding Mechanism for Barrel-Nailing Machines; and I do hereby declare the following to be a full, clear, and exact description thereof, such as will enable persons skilled in the art to which the invention pertains to make and use the same, reference being had to the accompanying drawings for a disclosure of one form in which my invention has been embodied.

The invention resides in a nail feeding mechanism for use with a machine for nailing the lapped ends of a strip of veneer forming boxes of the barrel type, and used generally for packing cheese.

The invention further consists of details which will be specified in the claims.

In the accompanying drawings, Figure 1 is a view in side elevation of a barrel nail-
ing machine provided with my improved nail feeding mechanism.

Fig. 2 is an enlarged plan view, partly in section of parts of the tack feeding mechanism, the view being taken upon the line 2—2, Fig. 1.

Fig. 3 is an enlarged vertical section on the line 3—3, Fig. 1, looking in the direction of the arrow.

Fig. 4 is a plan view in section of the clutch mechanism for operating the hammer, the view being taken on the line 4—4, Fig. 3.

Fig. 5 is a detail view of a portion of the clutch, the view being taken on the line 5—5, Fig. 4.

Fig. 6 is an end elevation showing the drum and the devices for expanding and contracting the same.

Fig. 7 is a view looking from the right of Fig. 6 and showing a part of the same mechanism.

Fig. 8 is an end view looking from the right in Fig. 1 and showing the clutch mechanism employed to connect the drum with the driving means of the machine.

Fig. 9 is a vertical sectional view of the

clutch shown in Fig. 8, and showing also the means for transmitting the motion of the driving mechanism.

Fig. 10 is a sectional view of the guide by which the tracks are properly directed into the barrel when driven by the hammer.

Fig. 11 is a plan view of the same parts.

Fig. 12 is a partly sectional view of the means for releasing the separated tacks for passage into the guide shown in Figs. 10 and 11.

In the drawings, the main frame of the machine is indicated by the letter A. A motor B is mounted upon a cross member of the said frame, and through the belt b drives the belt pulley C keyed upon the shaft c, journalled in bearings at the rear of the machine.

A worm c¹, likewise fast upon the shaft c, engages a worm gear c² keyed upon the hub c³ of the clutch rim c⁴. The worm gear c² runs in a bath of oil c⁵, whereby lubrication of the worm and gear is effected in their constant rotation. The hub c³ of the clutch rim c⁴ is mounted upon a tubular shaft c⁶ journalled in bearings and running lengthwise of the machine. At its rear end the tubular shaft has fixed thereon a spider c⁷, to the oppositely extending arms of which are pivoted brake shoes c⁸, designed for engagement with the perimeter of the clutch rim c⁴. A shaft c⁹ rotates within the tubular shaft c⁶, and at its rear end carries a disc c¹⁰, at eccentric points upon which are connected the links c¹¹, the other ends of which links are pivoted to the brake shoes c⁸.

The drum D is set upon the front end of the tubular shaft c⁶, so as to rotate therewith when engagement of the shoes c⁸ with the clutch rim is effected. A lever d is set upon the projecting end of the shaft c⁹, at the front of the machine. By grasping the handle d¹ fixed to the longer end of the lever d, a limited rotary movement may be given to the shaft c⁹ and through the eccentric action of the disc c¹⁰ bring the brake shoes c⁸ into engagement with the clutch rim, which as before stated is constantly rotated. The drum D is formed of two parts d² and d³, the part d² being carried upon spiders,

which at their hubs constitute the means for fastening the said drum upon the tubular shaft. The part d^3 of the drum is pivoted at d^4 just inside the periphery, and a slight clearance is provided near the pivotal point, between the longitudinal edges of the parts d^2 and d^3 , into which may be passed the end of the strip of veneer to be wound about the drum.

10 The opposite arm d^5 of the lever d is provided with a radial slot d^6 in which works a pin d^7 attached to one arm d^8 of a toggle joint d^9 . One member of the toggle is carried by the part d^2 of the drum and the other member thereof by the part d^3 . When the toggle is straightened, the drum is expanded, and likewise when the toggle is broken the drum is contracted. A loop d^{10} attached to the part d^2 of the drum serves 20 to prevent the toggle from passing beyond its straightened position in expanding the drum. One member of the toggle is provided with provisions for screw adjustment, whereby the diameter of the drum may be 25 adjusted with precision. A spring d^{12} connecting the arm d^8 with the part d^2 of the drum tends normally to straighten the toggle.

When the drum is collapsed by breaking 30 the toggle joint the adjacent longitudinal edges of the parts d^2 and d^3 , hereinbefore referred to, are separated for the insertion between them of a strip of veneer, and when the toggle is straightened, the pivoted part d^3 of the drum is expanded to its outer 35 position, with the result that the end of the strip of veneer is held between the adjacent edges of the drum near the pivotal point d^4 . The inner end of the radial slot d^6 is cut out as shown at d^{11} , for the purpose 40 of permitting a slight further movement of the lever d with the effect of more firmly setting the brake shoes in their engagement with the clutch rim c^4 , following the 45 straightening of the toggle and the expansion of the drum to its full diameter. The drum now being coupled up to the driving mechanism is rotated with the result that the strip of veneer is wound thereupon.

50 In the rotation of the drum, the strip of veneer is carried under and guided by a clamping bar E which stands normally a little above the surface of the drum, but which may be brought into clamping engagement with the strip after the latter has 55 been wound upon the drum by means of a treadle T pivoted to a part within the frame, and connected to the said clamping bar by a link e .

60 The clamping bar E is mounted upon a pivot e^1 secured in a standard e^2 at the rear of the frame, so as to provide for vertical adjustment of the pivot, to secure parallelism of the clamping bar. It will be understood 65 that after the strip of veneer has

been wound about the drum, such strip will be clamped thereto by the said bar upon pressure being applied to the treadle T and that the strip will be so held upon the drum while the tacks are driven into 70 the lapped ends of the veneer.

A slide F is mounted for longitudinal movement in a dovetailed channel in the clamping bar E . A standard G rises from the slide F and carries at the upper end thereof a receptacle g into which the tacks to be used in the machine are dumped. A wheel g^1 with a roughened surface is journalled at the upper end of the standard and works through an opening in the front end 80 of the receptacle g . Parallel bars g^2 and g^3 are supported by the standard G with their rear ends under the receptacle g , and inclined to the front of the machine. The said bars g^2 and g^3 are separated a distance 85 which will permit the shank of a tack to pass between them but will retain the tack by reason of the engagement of its head with the top surfaces of the said bars. It will be observed that a triangular space g^4 90 is provided at a point below the bottom level of the receptacle g , and forms a pocket into which the tacks will fall and come in contact with the roller g^1 . A shaft H is journalled in a bracket h attached to the 95 rear end of the slide F . Rotating loosely upon the said shaft is a grooved pulley h^2 , and fixed so as to rotate with the wheel g^1 is a like grooved pulley h^3 . A crossed belt h^4 transmits the motion of the constantly 100 driven pulley h^2 to the wheel g^1 . Formed as a part of the pulley h^2 is a sprocket h^1 . Upon the constantly driven shaft e is a sprocket c^{10} , and a third sprocket c^{11} is carried at the upper end of a swinging lever 105 c^{12} mounted upon the frame of the machine at the front end thereof, as indicated in Fig. 1. A sprocket chain c^{13} passes about the sprocket wheels c^{10} , h^1 and c^{11} so that the said sprocket wheels are constantly 110 driven. A spring c^{14} attached at one end to the frame and at the other to the lever c^{12} permits the sprocket c^{11} to have a yielding movement to compensate for any inequalities of the travel of the sprocket chain, 115 during the movement of the slide F , as will be later described. In the operation of the machine there is considerable vibration, and the result of such vibration is to cause the tacks to gradually work their way into the 120 pocket g^4 of the receptacle g , where they come into contact with the roughened surface of the constantly rotating wheel g^1 . The tendency of the tacks under the vibration of the machine is to crowd against the wheel g^1 and the action of the latter tends 125 to repel the tacks with the result that their points find their way into the open slot provided between the downwardly inclined bars g^2 and g^3 . In actual operation of a 130

large number of these machines it has been demonstrated that the slot between the bars g^2 and g^3 is constantly supplied with a succession of tacks all properly pointed for 5 action by the tack driving hammer when released and guided thereunder by the devices provided for that purpose.

Near their front ends the bars g^2 and g^3 are supported by a standard g^5 rising from 10 the slide F. Upon an arm of this standard is centrally pivoted at g^6 an escapement lever g^7 to which is imparted a lateral vibration about its pivotal point. The part 15 designated I is the lever for operating the tack driving hammer, the said lever being centrally pivoted at i to the slide F. Above its pivotal point rises an arm i^1 which is perforated at i^2 . The curved rear end g^8 of the escapement lever g^7 passes through the perforations in the arm i^1 , and as the lever I oscillates upon its pivot, the escapement lever is given a movement of vibration. The 20 escapement with which the said lever g^7 is provided is comprised of a curved pin g^9 and a straight pin g^{10} , the oppositely pointed 25 ends of which are sufficiently spaced in the direction of the length of the escapement lever to permit the shank of a single tack to pass between them upon each oscillation of 30 the said escapement lever. The construction and operation of the escapement is clearly shown in Fig. 2. In order to prevent damage by reason of the engagement 35 of the pin g^{10} with the shank of a tack as it passes down the channel formed by the separated bars g^2 and g^3 , I mount the said pin in the end of a spring g^{11} , which spring is secured to the outer side of the escapement lever. In case the point of the pin g^{10} 40 should encounter the shank of a tack in its passage down the slot, the spring will yield, but upon the next oscillation of the escapement lever will be released. In Fig. 2 I have shown the forward end of the escapement lever in the position of its outward throw, the forward tack in the slot resting 45 against the end of the pin g^9 . The reverse movement of the escapement lever will cause the pin g^9 to withdraw its support of the tack, and free the same for passage into the 50 tubular duct for conveyance to position under the hammer, and at the moment of such reverse movement of the escapement lever the pin g^{10} will pass in front of the second tack in the line and so hold the tack until 55 after the said pin g^{10} is withdrawn. Whereupon the tack then released will pass into engagement with the pin g^9 . It is believed 60 that the operation of this escapement mechanism will be understood without further explanation.

In my improved machine I have provided 65 in addition to the escapement devices, a dropper which will catch the tack released by the escapement and at the proper moment

permit the said tack to fall into the conveyor duct. This dropper is formed as a slide J having a longitudinal movement in guides j , with respect to the slide F. The front end j^1 of the slide J is bent at a right angle and carries a double pointed pin j^2 which is shown in Fig. 2 as extending immediately under the discharging end of the slot formed by the bars g^2 and g^3 . When released by the escapement devices the tack 70 will pass from the said slot with the shank between and the head thereof resting upon the double points of the pin. The slide J is provided near its mid length with a projection j^3 positioned for engagement by a pawl j^4 pivoted to the upper end of the arm i^1 of the hammer operating lever. The oscillations of the hammer operating lever I will cause the pawl j^4 , then in engagement with the projection j^3 , to move the slide J 80 forward, and withdraw the double pointed pin from its support of the tack, so that the latter is dropped point downward into the duct by 85 which it is conveyed to position under the tack driving hammer. A fixed cam j^5 upon which the pawl j^4 rides during the described forward movement of the slide J, acts to release the projection j^3 from engagement with the pawl. The rear end of the slide J 90 is encircled by a spring j^6 confined between one of the bearings for the slide and a pin j^7 passing through the end of the slide. The forward movement of the slide J under the action of the pawl j^4 serves to compress the 95 spring j^6 , but immediately upon the disengagement of the pawl, the said spring expands so as to impart a quick rearward movement to the slide and bring the double pointed pin of the dropper mechanism in 100 position to catch the next tack when released by the escapement. 105

A delivering guide or nozzle K for positioning the tacks under the hammer, is attached to the front end of the slide F and to this guide or nozzle the tacks released by the double pointed pin j^2 of the dropper devices are conveyed through a duct k . The nozzle K is composed of member k^1 which guides the tack hammer k^2 and two separable members k^3 and k^4 which are spring 110 pressed upon the member k^1 as shown in Fig. 10. A screw k^5 passes through the member k^3 and is threaded into the member k^4 . A spring k^6 confined between the head of the 115 screw and the member k^3 acts to hold the parts in position, and yet permits them to separate when a tack is forced between them by a blow of the hammer. Ribs k^7 on the bars k^3 and k^4 take into correspondingly formed grooves in the front and back of the member k^1 and maintain the vertical relation of the said members k^3 and k^4 with the part k^1 . The forward end of the hammer 120 operating mechanism is notched as indicated 125

at i^{10} in Fig. 1, for the reception of the head of the hammer h^2 . The hammer is positively actuated by a crank mechanism driven from the shaft H , the rear end of the lever I being slotted at i^{11} to receive the pin of the crank i^{12} , fixed to the said shaft H . Rotation of the shaft H with its crank will therefore impart movement to the hammer to drive the tacks. The shaft H is coupled to the sprocket h^1 by means of a novel form of clutch. The hub of the sprocket wheel h^1 is bored out for the reception of a clutch member L which latter is channeled longitudinally for the reception of a rocking member l . When the said rocking member l is in normal position in the channel of the clutch member L , the latter has an unbroken circumference, but when the said rocking member l is released it will be given a movement of partial rotation in the channel so that one edge thereof will project above the peripheral outline of the hub, and be in position to engage any one of a series of notches l^1 formed axially in the hub of the sprocket h^1 . The movement of the rocking member is due to the force of an expansion spring l^2 confined between the arm l^3 of the rocking member and the side wall of a slot formed in the said clutch member L . When the engagement of the rocking member l with one of the notches l^1 is permitted as described, the constantly rotating sprocket wheel h^1 will immediately couple the shaft H and rotate the crank i^{12} and operate the hammer to drive a tack with each rotation of the shaft H .

A rock shaft M supported parallel with the slide F , and operated with a handle m at its front end, is provided at its rear end with two arms or extensions which control the rocking member l as to its clutching engagement with the sprocket h^1 . The arm m^1 of the shaft M is provided with a projecting finger designed to hold the arm l^3 of the rocking member l in the full line position shown in Fig. 5 in which position the clutch member L will have an unbroken circumference. The arm m^2 on the shaft M is designed to engage a projecting lip m^3 on the projection part of the clutch member L and prevent the movement of the said clutch under the influence of the spring l^2 .

By means of the handle m on the shaft M the slide F is drawn to the front of the machine, and while in this position the handle is turned so as to rock the shaft m and release the arms m^1 and m^2 with their engagement with the clutch. Immediately the spring l^2 turns the rocking member l so that engagement thereof with one of the notches l^1 in the hub of the sprocket h^1 is effected and the shaft h^1 is rotated so as to drive a tack with each oscillation of the lever I . A notched rack or bar m^4 supported on the frame of the machine in a plane below the

path of movement of the slide F , is engaged by a pawl m^5 pivoted to the oscillating hammer lever I . With each oscillation of the lever I the pawl in engagement with one of the notches of the rack m^4 will drag the slide backward a distance equal to the spacing of the notches in the bar m^4 , with the result that the slide is traversed step by step along the winding drum and a tack is driven upon each movement. As soon as the tack driving mechanism has traversed the width of the barrel being formed upon the drum the operator releases his control of the handle m , and a coil spring m^6 attached at one end to the shaft M and at the other to the slide L , acts to throw the arms m^1 and m^2 before referred to into engagement with the parts of the clutch to separate the same and permit the machine to run idle. The drum may then be collapsed by turning the lever d so as to break the toggle and the barrel or hoop will be removed therefrom.

A spring f interposed between the frame and the lower side of the slide E , serves to support the latter in its normal position above the drum, and provides the clearance through which the strip of veneer is passed to be gripped by the clamping jaws of the drum.

A novel movement in the operation of my improved invention, and to which I desire to call particular attention is that the tacks are automatically passed from the receptacle g into the slotted guide formed by the bars g^3 and g^4 . So successful is my machine in its operation in this particular, that the said receptacle will become entirely emptied of tacks, in the continued operation of the machine. This result is due to the violent agitation constantly going on among the tacks in the said receptacle. The pawl m^5 engaging the toothed rack m^4 imparts a quick movement to the rear, of the slide F and the parts carried thereby, including the receptacle g . The tendency of this movement is to cause the tacks in the receptacle to crowd to the front end thereof and fall into the pocket g^4 , where they are brought into contact with the rotating wheel g^1 . The blow of the hammer in setting a tack is of such force as to impart a great vibration to the mass of tacks in the receptacle, and tends to produce a separation of the tacks in the mass. These operating conditions serve to cause the feeding of the tacks into the slotted guide in what is practically a continuous stream, and such tacks as are not presented to the wheel with their points properly positioned in the slotted guide will be repelled until presented in proper position to pass under the wheel and out of the receptacle g .

Modification of the invention may be made without departing from the spirit thereof.

Having thus described my invention, what I claim and desire to secure by Letters Patent of the United States, is:

1. A tack driving machine comprising a frame, a slide guided therein, a stationary tack receptacle supported upon the slide, a wheel rotating within the receptacle to position the tacks, an inclined slotted guide leading from the receptacle through which the tacks pass when positioned by the rotation of the wheel, in combination with a vibrating lever provided with devices to pass the tacks singly from the said guide, means for vibrating the said lever, a dropper to sustain the tacks when released from the slotted guide, nailing devices mounted upon and movable with the slide, and means for actuating the vibrating lever and the dropper so as to release the tacks for action by the nailing mechanism. 30 35
2. A tack driving machine comprising a frame, a slide guided therein, a stationary tack receptacle supported upon the slide, a wheel rotating within the receptacle to position the tacks, an inclined slotted guide leading from the receptacle through which the tacks pass when positioned by the rotation of the wheel, in combination with a vibrating lever provided with devices to pass the tacks singly from the said guide, a mov- 40 45 50 55
3. A tack feeding mechanism for a tack driving machine having a slide intermittently moved during the operation of the machine and carrying the tacking mechanism, comprising a stationary receptacle mounted upon the slide, an inclined slotted guide leading from said hopper and mounted on the slide, a rotatable member disposed over said guide adapted to repel any tacks not properly received in said guide, means to rotate said member, tack feeding means in said guide adapted for releasing one tack at a time, means for actuating said tack feeding means, a dropper carried by said slide adapted to sustain tacks released by said tack feeding means and means for actuating said dropper to deliver tacks to the tacking mechanism. 60 65

In testimony whereof I have signed my name at Milwaukee, this 14th day of February, 1920.

H. E. COOLEY.
